UNITED STATES PATENT OFFICE.

GILES F. WILLIAMSON, OF SAVANNAH, GEORGIA.

STILL FOR EXTRACTING TURPENTINE FROM GUM AND ROSIN.

No. 878,701.

Specification of Letters Patent.

Patented Feb. 11, 1908.

Application filed June 6, 1907. Serial No. 877,607.

To all whom it may concern:

Be it known that I, GILES F. WILLIAMSON, a citizen of the United States, residing at Savannah, in the county of Chatham and State of Georgia, have invented certain new and useful Improvements in Stills for Extracting Turpentine from Gum and Rosin, of which the following is a specification.

This invention relates to stills for extracting turpentine from gum and rosin.

In running a charge, great care is taken that the turpentine of the charge or mass within the kettle shall not exceed 316° F. nor fall below 212°, a mean between these extremes being maintained by "watering" or adding water to the charge in the kettle, or urging or moderating the fire, or both. In practice, the condition and needs of the charge is determined by the "singing" of the kettle which the distiller gets from placing his ear near the spirits pipe, which leads from the lower coil of the condenser to the exterior of the condenser near the bottom, and to effect any change in the water supply he must climb the steps leading to the platform or floor just below the still cap, in order to adjust the valve of the water supply pipe, which entails much labor, as the operation may have to be repeated many times during the working of one charge of the kettle.

One object of my invention is to avoid the objection above noted and so arrange the water supply pipe that the valve is accessible to the attendant while listening at the spirits pipe.

A further object is to arrange to supply the kettle with water of different temperatures, according to the requirements or conditions of the charge therin.

With these and minor objects in view, the invention consists of the matters described in detail in this specification, and briefly set forth in the claim.

In the accompanying drawing Figure 1 is a side elevation, partly in section, of a still embodying my invention. Fig. 2 is a detail showing a folding connection of the kettle.

In turpentine stills of the type shown, commonly used in the pine belt of the South and of ordinary size, the kettle 1 and condenser tub or tank 2 are supported about four feet above the floor of the still house, and rise through a flooring or platform A arranged at a distance below the top of the kettle 1 convenient for attendants to charge the kettle etc., the tub or tank 2 rising some

two or three feet or more above the top of the kettle, and during operation, having a water level maintained therein some two feet above the body of the cap 3, a valved water connection being arranged to lead from the upper part of the tub 2 to the cap 3 so that water may be fed to the kettle when needed. The water is usually supplied to the tub 2 at the bottom, and becomes hot at the upper end 65 of the tub, from rising in contact with the worm 4 containing the hot turpentine vapors.

In carrying out my invention, I provide for supplying water to the charge in the kettle from the upper end of the condensing tub, 70 as heretofore, and also, for supplying cold water from the lower end of the tub, as will be hereinafter explained.

Referring to the drawings, the kettle 1 and condenser tub 2 are, as usual, arranged side 75 by side being supported above the floor of the still room by the walls of the furnace and by a stout frame of usual construction and unnecessary to illustrate. The cap 3 of the kettle is fashioned with the usual goose-neck 80 and pipe which convey the turpentine vapors from the kettle to the condensing coil 4, located in the tub 2, the lower coil of worm terminating in the spirit pipe 5 which conveys the condenser vapors or turpentine 85 spirits to barrels for storage or shipment.

Cold water is fed to the tub 2 in various ways, as for instance by means of a duct 6 secured within the tub and open at top and bottom, whereby the cold water is discharged at the bottom of the tub adjacent to the lower end of the worm, the water as it rises in the tub toward the overflow 7 becoming heated, from contact with the worm.

A pipe 8 leads from near the top of the tub 90 downward into proximity of the spirit pipe 5, where it is provided with a valve 9, and passes thence upward to a bracket 10 where it is rigidly secured, and leads from there to the funnel 11 of the cap through jointed 100 pipes 12, 13, 14, 15, or through a rubber hose. The jointed pipes when used are so arranged that the length 13 may be folded up or down by the elbow union 12, and the pipe length 15 be in like manner turned up 105 or down on the elbow union 14, in order that this pipe connection with the funnel 11 of the kettle cap may be folded snugly against the side of the tub when workmen are charging or clearing the kettle, so that there will be no 110 interference with their movements in conducting their work. As shown, the pipe 8

passes beneath the tub, but it may be wound in a half coil on the exterior of the vertical walls of the tub, or if a flexible rubber hose is used (which may be desirable for extinguishing fire, or for spraying the dust laden floor of the still house) it may be connected with the pipe 8 adjacent to the discharge side of the valve 9, and disposed of as a skilled workman would see fit.

10 Beyond the discharge side of the valve 9, the pipe 8 is tapped with a short connection 16 from the interior of the tub, said connection being controlled by a valve 17 to permit or prevent passage of cold water from the bottom of the tub to the pipe 8 beyond the respective valves 9 and 17. From this construction it will be apparent that, the pipe 8 being connected with the funnel of the cap of the kettle, the distiller listening at the spirit

pipe to the "singing" of the kettle, may 20 without changing position manipulate the valves 9 and 17 to supply more or less warm or cold water to the kettle, according to circumstances.

Claim:

25 In a turpentine still the combination with the kettle and tub, of a watering pipe connection leading from the upper and lower ends of the tub to the kettle and valves for said connections located adjacent to the 30 spirit pipe to control the flow of water to the kettle.

In testimony whereof I affix my signature, in presence of two witnesses.

GILES F. WILLIAMSON.
